(57) CLAIM

The ornamental design for an eyeshadow box as shown and described.

DESCRIPTION

FIG. 1 is a front, left and bottom side perspective view of an eyeshadow box showing our new design;
 FIG. 2 is a rear, right and top side perspective view thereof;
 FIG. 3 is a front elevation view thereof;
 FIG. 4 is a rear elevation view thereof;
 FIG. 5 is a left side elevation view thereof;
 FIG. 6 is a right side elevation view thereof;
 FIG. 7 is a top plan view thereof;
 FIG. 8 is a bottom plan view thereof;
 FIG. 9 is a view showing the product in use; and,
 FIG. 10 is another view showing the product in use.
 The broken lines shown in the drawings represent portions of the eyeshadow box that form no part of the claimed design.
